UNITED STATES PATENT OFFICE.

JAMES C. SHULTS, OF MEADVILLE, PENNSYLVANIA, ASSIGNOR TO RUSS AUTOMATIC LABELING CO., OF NEW YORK, N. Y., A CORPORATION OF DELAWARE.

CAN-LABELING MACHINE.

1,061,021.

Specification of Letters Patent.

Patented May 6, 1913.

Application filed September 2, 1911, Serial No. 647,428. Renewed August 12, 1912. Serial No. 714,707.

To all whom it may concern:

Be it known that I, JAMES C. SHULTS, a citizen of the United States, residing at Meadville, in the county of Crawford and 5 State of Pennsylvania, have invented an Improvement in Can-Labeling Machines, of which the following is a specification.

My invention relates to improvements in machines for affixing labels to sheet metal 10 cans and similar articles containing canned commodities, articles of food, etc., and the same is designed as an improvement upon the device shown and described in Letters Patent granted to George F. Russ, November 2nd, 1909, No. 938897, with the object of 15 performing all the functions incident to feeding, moistening, pasting and conveying the labels from a receptacle to the can and feeding the cans, wrapping the labels around 20 the same in the most approved manner and delivering the labeled cans from the machine.

In the machine of my improvement, the labels in a superposed pile are placed in a 25 suitable receptacle from which they are removed one at a time from the bottom of the pile. The labels are progressively fed to and through a device,—I designate a humidor—in which the labels are moistened 30 with water and hot vapor. The labels are then progressed to a pasting device, where the unprinted and uppermost surfaces are given a coat of paste or suitable adhesive material and the labels as pasted, forwarded 35 by endless conveyers to meet the cans. The cans are fed to the machine one at a time and at the end of the feed are engaged at their ends by revoluble yielding clamps. The pasted labels are fed on to an endless apron 40 having a moistened surface and a swinging arm associated with the apron elevates a part thereof encircling the same with the label around the can. As the can revolves, the label is caused to adhere thereto by the 45 pressure of the apron. This arm moves downward to an initial position after the wrapper is pasted on the can, the clamps are released and the can rolls down the apron and away to a suitable receptacle, the 50 operations as stated, being successively repeated with each can.

The fuller recital of the device and the operations thereof will hereinafter be more particularly set forth.

55 In the drawing, Figure 1 is a diagram-

matic longitudinal section representing the essential features of my invention. Fig. 2 is a side elevation especially representing the device for operating the several parts of the machine. Fig. 3 is a plan of the right hand 60 end of the machine of my improvement. Fig. 4 is a plan of the left hand end of the machine of my improvement. Fig. 5 is an elevation at the rear end of the machine. Fig. 6 is a vertical cross section through the 65 machine at the humidor or label moistening device. Fig. 7 is a vertical section representing the preferred form, or group of devices for applying the label to the can. Fig. 8 is an elevation showing the intermediate 70 gear devices for raising parts associated with applying the label to the can.

Similar letters and numerals of reference indicate the same parts.

The rectangular open frame is preferably 75 mounted on corner legs, shown especially in Figs. 1 and 2, the same supporting the devices of the entire mechanism, and I prefer to employ a device for holding a pile of superimposed labels, similar to the device 80 shown in the before named Russ Patent No. 938897, in which 2 represents a side and 3 an end of the receptacle, 4 represents the bottom of the receptacle and 6 represents pins that are upright and adjustable and 85 which form the substantial equivalent of the other side of the receptacle, stops being provided for the pins.

a represents a shaft in suitable bearings and a' segments on this shaft a, which by 90 preference are rubber-faced. The bottom or support 4 for the labels is cut away so as to provide for the operation of the segments a' a'. These segments, in their rotation with the rotation of the shaft a, take hold 95 of the bottom or lowermost label and advance the same out from beneath the pile of superposed labels into the bight of the forwarding rollers 5.

The devices for moistening the labels with 100 water and hot vapor and which I term "a humidor," comprise a wheel or drum b preferably with hollow trunnions and spokes b' from the trunnions to the periphery of the wheel. The trunnions are mounted in bearings b² and I prefer and have shown pipes c as connected to an X-head extending from a pipe c² through the trunnions and the pipes c terminating in arms c' which are perforated 105 specially on their outer surfaces. These 110

5 pipes remain stationary while the wheel or drum rotates around the same, steam being contained in the said pipes and emerging within the drum or wheel through the perforations in the arms c' .

6 d represents a tank for water supported from a floor or other convenient support and in the same is a vertically movable weighted roller d' .

10 e represents the endless belts of a series; e' a series of rollers mounted between side inclosing plates f , and e^2 larger rollers at the upper part. The endless belts e pass around the greater portion of the drum or 15 wheel b , over the rollers e^2 and outside the rollers e' and under and beneath the weighted roller d' through the water of the tank.

18 The wheel or drum b has preferably 20 around the same a band of felt f' which comes between the same and the endless belts e , and the labels as they are removed progressively from the superposed pile in the receptacle, pass between the rollers 5 25 over the belts e , around the right hand roller e^2 and then down between the said belts and the felt covering f' on the wheel b , being guided in their movements by a series of vertically disposed guiding blades e^3 supported upon the stay-bars e^4 and which 30 guide blades are spaced across the surface of the wheel or drum b and its felt cover. The belts e become wet as they pass through the water in the tank d and consequently 35 they thoroughly moisten the felt covering f' of said wheel or drum. The heat of the wheel or drum from the steam within, heats the felt so that the moisture thereof is being constantly evaporated in the form of a 40 heated vapor, and as the labels pass between the belts e and the surface of the roller, they are not only thoroughly moistened but considerably heated. However they are not moistened sufficiently to be so saturated as 45 thereafter to drop any water in their movement through the machine. The labels pass almost entirely around the wheel or drum in transit and on the opposite side are guided by the blades e^3 over the left-hand 50 roller e^2 and into the devices of the machine to be pasted. Adjacent to these parts is located a paste or adhesive material holder g in the form of a trough, in which is located a roller g' . By its revolution, this 55 roller g' lifts out of the trough on its surface the paste or adhesive material. A distributing roller g^2 running in contact with the roller g' and in the opposite direction thereto, removes the paste or adhesive material at least to a required extent from the 60 surface of the roller g^2 , and the labels as they pass over the left-hand roller e^2 and the belts thereon, are lifted by the switch wires 9 and directed toward the rollers 7 , 8 ,

65 the labels then passing between the rollers

7, 8 , and the pasted surface of the distributing roller g^2 and the upper and unprinted surface of the label then receives a coat of paste or other adhesive material. The switch fingers 10 prevent the labels passing 70 farther upon the surface of the distributing roller g^2 and direct the said labels forward on to the endless conveyer h which is composed of several belts. These belts pass around the rollers 11 and 13 and over the 75 opposite faces of the rollers 12 . Associated with the endless conveyer h is an auxiliary conveyer composed of belts i mounted on the rollers 14 , 15 , and the belts of which are provided with the alining metal ribs i' having 80 plate bases riveted to the belts. These ribs bear either upon the outer surfaces of the several belts h or upon the surfaces of the labels and tend to regulate and evenly progress such pasted labels, and in this connection I employ guide rollers i^2 at one or both sides of the outer of the belts h for the purpose of shifting and straightening the labels upon the conveyer belts so that they 85 run regularly and true.

90 I have shown and prefer to employ a tension roller h' adjacent to the rollers 13 and which tension roller is provided with suitable supports and adapted to bear upwardly against the upper parts of the conveyer 95 belts h so as to press the same toward the auxiliary belts i . It is preferable to employ a nut for raising and lowering the tension rollers, and I prefer to employ a separate tension roller under each of the belts h so that tension to the desired extent may be had on any of the belts independent of the others. I also employ tension rollers i^3 to draw the belts i toward the belts h .

99 It will be noticed that the conveyer belts, 100 the ribs on the auxiliary belts and the tension rollers come closely adjacent to the delivery end where the pasted label is placed upon the can, and as these cans are of more or less uneven surface because of the ribs 110 and the edge of the cover or lid, it is a fact that more tension is required on the side of the label that goes over the lid and bead than on the other side, so as to appreciably stretch this edge of the label, whereby when 115 the entire label is on the can the edges of the label lap-up even and parallel. This required tension is imparted by either or both of the rollers h' and i^3 and the adjustable devices supporting the same, whereby more 120 or less force is applied which causes the ribs i' to bear against the pasted labels upon the belts h , holding the same and retarding their free discharge from the support of these belts h to the bite of the apron 125 k and the can being labeled.

130 The devices for wrapping the label on the can and for supplying the cans one at a time to said devices, consist of the following parts:—An endless apron k passes

around rollers 16, 17 and 18, Fig. 7, the roller 18 being just above the water in the tank. A brush roller 19 is employed in the tank and provided with means for rotating the same in a direction opposite to the rotation of the roller 18, for the purpose of continuously wetting the surface of the apron *k* and removing from the surface of the apron or belts any free paste that may have been delivered thereon and squeezed out from between the label and the can as the label is pasted on the can, and so washing the apron that when the apron leaves the tank of water, it leaves the same clean without any paste or other particles. A pair of swinging arms *k'* are upon the shaft of the roller 17 and their free ends carry a roller *k''* around which the apron also passes.

20 I provide heads 20 adapted to come against the respective ends of the can; these heads are formed with spindles 21 passing through suitable bearings *n*. Each spindle is provided with a cam 22 and there is an adjacent fixed arm 23 having a pin acting in the groove of said cam for moving the said spindles and heads, one or both, in opposite directions, so as to open and close the distance between the heads 25 to receive the cans as delivered, and thereafter to release the same. In each bearing *n*, around the spindle 21, is a spring 24, serving to make steady the movement of the spindles in pressing the heads against the ends of the cans to hold the same tight and in taking up any lost motion. The arms 23 are fixed upon or formed with the bearings for the shaft 21 on the upper ends of standards *o'*.

30 I provide one or more standards 25 and one or more arms 27 pivoted thereto. Each arm 27 has a projection and roller, which latter bears upon the surface of the cam 26 provided for raising and lowering the arms 27. Upon the free ends of the arms 27 are heads 28, concave on the under sides to a slightly greater area than that of the can, and the lower parts of these heads, on the inner faces, are provided with spring dogs 35 29, for supporting the can at its opposite ends.

I provide a swinging arm 30 pivoted to guide arms 31 secured to an inclined platform 32 down which the cans to be labeled descend by gravity. This arm 30 is also pivotally connected to the head 28 by a sliding pivot 33,—that is a pivot sliding or moving in a slot in the top of the head.

40 A power shaft *o* runs along one side of the machine and is mounted in suitable bearings in the upper ends of the standards 34, and I provide a pair of bevel gears 35 for operating the right hand roller *e''*, and line gears 36 for actuating the rollers 45 5. I also provide bevel gears 37 for actu-

ating the left hand roller *e'* whereby motion is communicated through the rollers *e'* to the endless belts *e* and therefrom to the wheel or drum *b* for the operation of moving the labels one at a time through the 70 humidior. I also provide bevel gears 38 adapted for actuating the line gears 39 and the pasting rollers *g', g''*. Bevel gears 40 communicate motion to the roller 11 and therefrom to the endless conveyer belts *h* 75 while bevel gears 42 also communicate motion to the rollers 12 and 14 of the belts *h* and auxiliary belts *i*. Bevel gears 41 are employed to transmit rotation from the power shaft *o* to the cam 26, so as to operate 80 the arm 27 and the cam actuating devices.

In connection with forwarding the labels as pasted over the endless conveyer belts *h*, I have shown and prefer to employ series of guide rollers *i'* which serve while the 85 pasted labels are lying loose and free on the belts *h*, to straighten the same if the edges are out of true right angle with the line of travel.

At the end of the power shaft *o* there are 90 standards *o'* and on the end of the power shaft there is a pinion 43, meshing with the bevel gears 44 and 45. The bevel gear 44 is on the shaft 51 and the bevel gear 45 is on the shaft 46^a in a standard *o''*.

On the shaft 48, in bearings in the standards *o'*, there is a gear 47 meshing with the gear 46, and also intermittent gears 49.

I have shown in Figs. 2, 7 and 8, on the revoluble parts, arrows which show the direction of rotation. Fig. 8 shows one of these intermittent gears 49 as containing a few teeth and a plain radial surface, and also in Fig. 8 one of the arms *k'* and the hub end of said arm which contains teeth and a concave surface 50, the teeth being in mesh with the teeth of the intermittent gears 49; therefore as the gears 49 are rotated by their shaft 48 through the medium of the gear 47, the gear 46, bevel gear 45 and the conical pinion 43, these intermittent gears turn in the direction of the arrow and raise the arms *k'*, elevating the same into the position of said arms shown in Fig. 2, and when in this position, the concave surfaces 50 of their hubs,—the arc of which agrees with the arc of the surface of the intermittent gears 49,—holds the arms *k'* in the elevated position until the intermittent gears 49 come around to their reduced diameter, 110 at which point the arms *k'* are permitted to fall into the position shown in Fig. 7, at which time, in the timing of the movements of the machine, the cans have been labeled and are prepared to roll down the belt *k* to 115 a suitable receptacle.

On the shaft 51 to which rotation is imparted by the shaft *o*, through the conical pinion 43 and the bevel gear 44, there are connected gears 52 and on the shaft 21 there 130

are the large gears 53 meshing with the gears 52 and receiving their rotation therefrom. The heads 20 between which the cans to be labeled are clamped, are also connected upon these shafts or spindles 21 so that rotation is imparted to the cans as labeled, by the gears 53 and 52, and the shaft 51.

In the further operation of the device and with special reference to Fig. 7, as the arms 27 are moved up and down by the cam 26, the swinging arm 30 is moved downward into the position shown in Fig. 7 and its curved left hand end partially encircles the foremost can on the platform 32 and keeps the same in position while the grip of the said arm 27 and its head 28 upon the can held thereby, brings said can down into the true position between the heads 20 where the can is clamped, and in the timing of the parts, at once the can is clamped, the arm 27 and head 28 are quickly raised and the spring dogs 29 yield over the surface of the can as held, and as the arm 27 and head 28 again come up into the position shown in Fig. 1, the arm 30 at its left hand end, releases the advancing can and the same rolls down into the head 28 supported by the spring dogs 29; the left hand end of the arm meanwhile bears against the second can so as to prevent the same rolling forward until the next downward movement of the parts in repeating the operations.

I have shown at 54 in connection with the distributing roller g^2 and its gear 39, means for adjusting the position of this distributing roller with reference to the several parts associated therewith.

In the further operation of the device of my improvement, the swinging arm 30, as in Figs. 1 and 7, controls the can at the end of the inclined platform 32, preventing the same shifting as the can-holding devices move down to deliver a can and rise empty. The heads 28, at the end of the arm or arms 27, are slightly wider apart than the length of the can to be labeled, consequently, the cans come between them. In the position Fig. 7, the heads 20 engage the ends of the can and hold the same tight, and as the heads 28 rise, the dogs 29 over-run the can, and then spring into place ready to receive the next can, which is released from the platform 32, as soon as the arm 30 assumes the position Fig. 1, with the free bent end against the next advancing can. These spring dogs 29 are sufficient to hold the weight of each can. The heads 28 must be concave, as shown, to permit of the heads 20 coming up to and engaging the ends of the can. The apron k , with the pasted label thereon, is moved from the position Fig. 7 to the position Fig. 1, as soon as the can has been engaged by the heads 20.

I claim as my invention:

1. In a can labeling machine, devices for

forwarding labels one at a time from the bottom of a superposed pile, revoluble devices for moistening the labels, devices for pasting the unprinted surface of each label, conveyer devices receiving and for moving the pasted labels from the pasting devices, auxiliary devices for applying tension in transit to the pasted labels, devices receiving, holding, and for revolving cans to be labeled one at a time, an endless apron having a part running in proximity to the revolving can and receiving the label to be pasted thereon, swinging devices associated with the endless apron for diverting the path of part of the apron and wrapping the same partly around the can in the labeling operation and so pressing the label firmly upon the can.

2. In a can labeling machine, devices for forwarding labels one at a time from the bottom of a superposed pile, revoluble devices for moistening the labels, devices for pasting the unprinted surface of each label, conveyer devices receiving and for moving the pasted labels from the pasting devices, auxiliary conveyer devices for applying tension in transit to the pasted labels, devices receiving, holding and for revolving cans to be labeled one at a time, an endless apron having a part running in proximity to the revolving can and receiving the label to be pasted, thereon, devices for moistening the surface of said apron and removing therefrom any surplus adhesive material, swinging devices associated with the endless apron for diverting the path of part of the apron and wrapping the same partly around the can in the labeling operation and so pressing the label firmly upon the can.

3. In a can labeling machine, devices for forwarding labels one at a time from the bottom of a superposed pile, revoluble devices for moistening the labels, devices for pasting the unprinted surface of each label, conveyer devices receiving and for moving the pasted labels from the pasting devices, auxiliary conveyer devices for applying tension in transit to the pasted labels, devices receiving, holding, and for revolving cans to be labeled one at a time, an endless apron having a part running in proximity to the revolving can and receiving the label to be pasted thereon, swinging devices associated with the endless apron for diverting the path of part of the apron and wrapping the same partly around the can in the labeling operation and so pressing the label firmly upon the can, and devices receiving the unlabeled cans one at a time from a source of supply and delivering the same into the machine to be labeled.

4. In a can labeling machine, the combination with a receptacle for holding a superposed pile of labels and means for forwarding the labels one at a time from the bottom

- of the pile, of a wheel or drum, devices within the same receiving steam for heating the drum, a series of endless belts in parallel extending around the larger portion of said 5 drum, rollers around which the belts pass and for moving the same, a receptacle for water through which said belts pass, a weighted roller in said receptacle for holding said belts taut and beneath which they 10 pass, and guide blades above said drum whereby the labels one at a time pass between said drum and said belts and are deflected into and carried around between the belts and the drum and delivered from the 15 opposite side.
5. In a can labeling machine, and in combination, a receptacle for holding a superposed pile of labels and means for forwarding the labels one at a time from the bottom 20 of the pile, a wheel or drum having a solid periphery, hollow trunnions, intermediate spokes and bearings therefor, a felt strip around the periphery of said wheel or drum, a pipe for steam passing through one of 25 said hollow trunnions and provided with branching arms and discharge arms for the steam at right angles thereto within said wheel or drum whereby the drum and the felt covering are heated, plates at the sides 30 of said drum, rollers spaced around the drum and bearings in said plates, a tank for water beneath the drum, a loose vertically movable weighted roller in said tank, rollers in the upper part of said drum spaced apart 35 and having bearings in said plates, a series of guide blades between the latter rollers extending over the drum and its felt covering, and a series of endless belts arranged parallel and passing around all of the said 40 rollers through said tank beneath the weighted roller and with their inner portions in contact with the felt covering of the drum, whereby the felt covering is moistened and heated and the endless belts 45 are moistened and labels passed one at a time between the moistened belts and the moistened and heated felt covering for preparing the labels for the pasting operation.
6. In a can labeling machine, the combination with means for moistening the labels one at a time, of a receptacle for adhesive material such as paste, a roller therein, a distributing roller receiving the paste from the aforesaid roller, label supporting rollers 55 beneath the distributing roller but out of close contact therewith, switch wires for receiving the moistened labels from the moistening devices and directing their path to the paste distributing roller, and other 60 switch fingers for removing the labels as pasted from the paste distributing roller and diverting their path of travel.
7. In a can labeling machine, the combination with means for applying adhesive material to the surface of the labels and 65 diverting their path of travel, of a series of endless conveyer belts, rollers around which the same pass, a series of superposed auxiliary conveyer belts, strips of metal forming ribs secured to the said auxiliary conveyer belts across the same at right angles to their length and adapted to bear upon the endless conveyer belts for gripping the pasted labels and evening the same in transit, and means for applying pressure or tension to any one or a number of the endless conveyer belts as against the auxiliary belts and their ribs, whereby the pasted labels may be held in the desired places and perceptibly stretched, and means co-acting 70 therewith for applying the labels simultaneously to and around the cans.
8. In a can labeling machine, the combination with a series of conveyer belts for forwarding the pasted labels, of devices for progressing the cans to receive the labels, devices for engaging the cans at their respective ends and holding and rotating the same, an endless belt or apron receiving the pasted labels one at a time as forwarded, and suitable rollers upon which the same is mounted and devices connected with said apron and operated at predetermined intervals for moving the apron and one of the rollers and causing the same to be elevated and embrace 75 a part of the revolving can so that the label is partly wrapped around the can as pasted thereto.
9. In a can labeling machine, the combination with a series of conveyer belts for forwarding the pasted labels, of devices for progressing the cans to receive the labels, devices for engaging the cans at their respective ends and holding and rotating the same, an endless belt or apron receiving the pasted 80 labels one at a time as forwarded, and suitable rollers upon which the same is mounted, devices connected with said apron and operated at predetermined intervals for moving the apron and causing the same to 85 embrace a part of the revolving can so that the label is partly wrapped around the can as pasted thereto, and means for returning the apron to its initial position, whereby a part of the same in an inclined plane, forms 90 a delivery for the can as labeled and released.
10. In a can labeling machine, the combination with the power shaft and a conical pinion on one end thereof, of a bevel gear 120 and a shaft on which the same is fixed, a bevel gear and line gear and an arbor therefor, a shaft below the power shaft and a line gear thereon meshing with the aforesaid line gear, intermittent gears also on the 125 latter shaft, devices for engaging the opposite ends of a can to be labeled, and gears connected therewith and extending to the first aforesaid shaft for rotating the cans, an endless apron and devices operated by 130

said intermittent gears for imparting to the apron a swinging motion so as to wrap a part of the apron over the revolving can in pasting the label thereon.

- 5 11. In a can labeling machine, the combination with the power shaft and a conical pinion on one end thereof, of a bevel gear and a shaft on which the same is fixed, a bevel gear and line gear and an arbor there-
10 for, a shaft below the power shaft and a line gear thereon meshing with the afore-
said line gear, intermittent gears also on the latter shaft, devices for engaging the op-
posite ends of a can to be labeled, and gears
15 connected therewith and extending to the first aforesaid shaft, for rotating the cans, an endless apron receiving a series of rollers around which the apron passes, a pair of arms and pivots therefor, the free ends of
20 the arms carrying one of said rollers, the hub of said arms being provided with teeth engaging the teeth of the intermittent gears, and said hub also having a smooth concave portion 50 adapted to overlie the smooth
25 periphery of the intermittent gears for sup-
porting the arms and belts in an upright position and said gears also having a part of reduced radius permitting the arms and rollers to descend to an initial position.
30 12. In a can labeling machine, the combination with endless conveyer belts for for-
warding the pasted labels and devices for holding the can to be labeled, of an endless apron, rollers around which the same ex-
35 tends and by which the same is rotated, de-
vices for actuating said rollers, a tank for water and a brush roller in said tank, means for rotating the brush roller for moistening the surface of the endless apron and for
40 washing therefrom any surplus paste.
13. In a can labeling machine, the combi-
nation with endless conveyer belts for for-
warding the pasted labels and devices for holding the can to be labeled, of an endless
45 apron, rollers around which the same ex-
tends and by which the same is rotated, de-
vices for actuating said rollers, a tank for water and a brush roller in said tank, means for rotating the brush roller for moistening
50 the surface of the endless apron and for washing therefrom any surplus paste, de-
vices associated with one of the rollers

around which said endless apron passes, and means for actuating the same and raising the apron at one side so as to cause the 55 same to partially encircle the cans to be labeled to insure the perfect placing of the labels around the cans.

14. In a can labeling machine, an inclined platform down which the cans to be labeled 60 are delivered, a swinging arm and a head at the free end of said arm, a device piv-
otally mounted to said head and also piv-
otally mounted to a part of said inclined platform, and spring actuated can support- 65 ing devices connected to said head, whereby the cans one at a time are received from the said platform in said head and the cans on the platform restrained in their movement, and means for receiving from said head in 70 its lowest position the cans and holding the same, and other means for holding the ro-
tating devices.

15. In a can labeling machine, the combi-
nation with a power shaft, a shaft at right 75 angles thereto and a cam thereon, means for communicating rotation from the power shaft to the cam shaft, an arm and a suit-
able support to which the same is pivoted, a roller carried by said arm and actuated 80 by said cam to raise and lower said arm, a head upon the free end of said arm adapt-
ed to receive a can to be labeled, spring dogs connected with said head for carrying the weight of the can, a platform down 85 which the cans descend to be labeled, a swinging arm pivoted to a part of said plat-
form and having a curved end to pass over the periphery of the can, said arm at its free end being pivoted to said head in a 90 slot thereof, whereby when said head moves down with its arm, the pivoted arm swings and changes its relation to the head so as to hold back the cans on the platform in one position and in the other position to per-
mit the first can to rotate in the head and simultaneously hold back the second can.

Signed by me this 24th day of August,
1911.

JAMES C. SHULTS.
